(57) **CLAIM**

The ornamental design for an umbrella runner, as shown and described.

DESCRIPTION

FIG. 1 is a front view of an umbrella runner showing my new design; the new design for an umbrella runner is illustrated in an umbrella assembly shown in broken lines, the umbrella assembly being one non-limiting environment in which the new design can be used;

FIG. 2 is a top perspective view of the claimed umbrella runner;

FIG. 3 is a bottom perspective view of the umbrella runner of FIG. 2;

FIG. 4 is a rear view of the umbrella runner of FIG. 2;

FIG. 5 is a front view of the umbrella runner of FIG. 2;

FIG. 6 is a left side view of the umbrella runner of FIG. 2;

FIG. 7 is a right side view of the umbrella runner of FIG. 2;

FIG. 8 is a bottom view of the umbrella runner of FIG. 2; and,

FIG. 9 is a top view of the umbrella runner of FIG. 2.

The broken lines in the figures depict an umbrella assembly and portions of the umbrella runner that form no part of the claimed design.
